TRANSLATING PAPER MACHINE TUBE ROLL

William C. Nash, Neenah, Wis., assignor of one-fifth to Mary Jones, Neenah, Wis., one-fifth to William M. Nash, Chicago, Ill., one-fifth to Roy A. Nash, New Rochelle, N. Y., and one-fifth to Marie Duvall Nash, Neenah, Wis.

Application July 11, 1936, Serial No. 90,115

4 Claims. (Cl. 92—44)

This invention comprises a continuation in part of applicant's co-pending application, Serial No. 49,469, filed November 3, 1935 and relates to improvements in paper making machines, and refers specifically to an improvement in the tube rolls of a paper making machine of the Fourdrinier type, characterized in that the rotative speed of the tube rolls is controllable independent of the speed of translation of the Fourdrinier wire and, that the tube rolls create no undue disturbance of formation of the web upon the wire.

In the making of paper on a Fourdrinier type of machine, the pulp predominantly liquid, is discharged from the head box on to a moving wire or screen. The wire or screen passes over a series of tube rolls which contact the lower face of the screen and assist in the removal of the liquid from the pulp carried on the upper portion of the wire. The tube rolls are usually of relatively small diameter and are rotated by their contact with the moving screen.

Of course, since the tube rolls are rotated by their contact with the screen, the peripheral speed of the surfaces of said rolls will be substantially equal to the speed of travel of the screen, and the angular velocity of said rolls will depend upon the speed of travel of the screen and the diameter of the rolls. When operating the paper making machine at low speeds, the screen, of course, travels at relatively low speed and, hence, the tube rolls are not rotated at an excessive angular velocity. However, as the speed of travel of the screen increases, thereby increasing the angular velocity of the rolls, difficulty is encountered due primarily to centrifugal action of the rolls upon the liquid carrier of the pulp which seeps through the screen on to the rolls, and also upon the fact that the front sides of the rolls travel upwardly toward the screen and the rear or trailing sides of the roll travel downwardly and away from the screen. These phenomena, although present at all screen speeds, are accentuated at high speeds and tend to disturb the ideal formation of the fibres upon the screen. Further, due to the fact that this disturbance is caused by the combined effect of the liquid carrier and the speed of the rolls, it will be most pronounced at those rolls adjacent the head box since the pulp is dehydrated at a greater rate at its initial travel upon the wire than at the intermediate or final portion of its travel.

My invention is broadly directed to the elimination of this difficulty and resides in the pro-

vision of means for controlling the rate of rotation of the tube rolls, particularly those adjacent the head box. In other words, by the use of my invention, one of the above mentioned factors which cause disturbance of the fibres upon the screen is controllable.

To reduce the speed of the tube rolls, that is, to render the speed of the tube rolls independent of the speed of travel of the screen, I provide an arrangement whereby the axes of the tube rolls can be moved at a desired rectilinear speed in the direction of travel of the screen or contrary to the direction of travel of the screen. By correlating the speed of translation of the rolls with the speed of translation of the screen, the rolls can be caused to rotate at a peripheral speed substantially equal to the difference of said speeds of translation. This difference in speed may be either positive or negative, that is, if the speed of translation of the screen exceeds the translation speed of the rolls, the rolls will rotate at a peripheral speed equal to the difference in the direction of travel of the screen, or if the translation speed of the rolls exceeds the speed of the web the rolls will rotate in the opposite direction to the direction of travel of the screen. However, in controlling the rate of rotation of the rolls, as described, the ultimate function of the rolls, that is, to assist in the removal of the liquid carrier, is in no wise diminished.

Specifically my invention resides in the provision of an endlessly moving articulated conveyor upon which the tube rolls are mounted, the rolls being so mounted on the conveyor that the same may be periodically moved to position beneath the forming wire or screen without jarring or shaking the wire and disturbing the formation of the fibres carried upon the wire.

Other objects and advantages of my invention will be apparent from the accompanying drawing and following detail description.

In the drawing, Fig. 1 is a diagrammatic view of my improved tube roll arrangement.

Fig. 2 is a fragmentary sectional view taken on line 2—2 of Fig. 1.

Referring in detail to the drawing, 1 indicates one of two oppositely disposed side frames which may be positioned on opposite sides of a portion of the wet end of a paper making machine 2. A hanger 3 carrying an open bearing 4 is mounted upon an end of each of the frames 1 in which opposite ends of shaft 5 are journaled, said shaft carrying breast roll 6. A Fourdrinier wire or screen 7 passes around breast roll 6 in the con-

ventional manner and travels in the direction indicated by the arrow.

A sprocket wheel 8 may be mounted upon each side of the machine 2 adjacent the breast roll 6 and a sprocket chain 9 may travel around each of said sprocket wheels. In spaced relationship with each of the sprocket wheels 8 along the length of the machine 2, is a sprocket wheel 10, over which each of the chains passes. Sprocket chains 9 at the upper portion of their travel move in the same direction as screen 7, either wheels 8 or 10 constituting the driving wheels. However, the driving of the sprocket wheels is independent of the driving of screen 7 and, as will be hereinafter more fully described, the speed of the chains 9 and screen 7 is different so that there will be relative motion between the two.

Each sprocket wheel 10 upon each side of the machine is mounted upon a shaft 11 which is journaled in a bearing block 12, each of which, in turn, is slidably positioned in ways or guides 13 formed upon the support 14. A screw 15 operable by means of hand wheel 16 is threaded in the ends of the guides 13, and the ends of said screws are so associated with the blocks 12 that manipulation of hand wheels 16 move blocks 12 within the ways 13. By this arrangement the desired tension may be produced in chain 9.

The chains 9 carry a plurality of tube rolls 17 which are mounted upon shafts 18 at spaced intervals along the length of the chains. As an important feature of my invention the ends of shafts 18 comprise axes of articulation of the sprocket chains 9, that is, said ends serve as pivot pins which connect spaced links of the chains to adjacent links. The importance of this feature of my invention will be hereinafter more fully described.

The ends of the shafts 18 extend beyond the chains 9 and carry frictionless rollers 19. A frame 20 mounted upon frame 1 traverses a portion of the path of travel of chains 9, said frame 20 being provided with a laterally opening groove 21 which provides a track upon which rollers 19 travel. The width of the groove 21 is slightly greater than the diameter of the rollers 19 so that clearance is provided between the top of the rollers and the upper defining surface of the groove. The grooves 21 stop short of the curved portion of the path of travel of the chains around sprocket wheel 10 whereby said wheel may be moved to tension said chains.

In the paper making operation as heretofore practiced, wire 7 travels around breast roll 6 and immediately thereafter a quantity of pulp from the head box (not shown) is "flowed" upon the wire. The pulp, of course, immediately begins to dehydrate, that is, the liquid carrier flows through the meshes of the wire leaving the fibres deposited upon the wire surface. In the usual Fourdrinier machine the wire carrying the pulp passes over, and is supported by a plurality of tube or table rolls which are freely rotatable about their axes but are laterally immovable. Said tube rolls are rotated by movement of the wire and, hence, are rotated at relatively high speed when the paper making operation is rapid. Therefore, a portion of the liquid discharged through the screen surface is carried upon the surfaces of these rapidly moving rolls and by centrifugal force is thrown from the rolls at a rapid rate upwardly toward the bottom of the wire thus tending to disturb the fibres upon the upper surface of the wire. In addition this rotating action of the tube rolls builds up pressure zones

adjacent the screen at the advancing side of the rolls, and reduced pressure zones adjacent the screen at the receding side of the rolls. The pressure zone tends to lift the fibres from the screen surface and otherwise disturbs the original desired lay of the fibres. The reduced pressure zone tends to suck the fibres down upon the wire surface which causes objectionable wire marks upon the paper. In addition, pin holes are formed and a one-sided shade is imparted to colored paper. Consequently, the tube rolls of the conventional paper making machine constitute one of the most serious limitations to the speed of the machine.

It can readily be seen therefore, that by controlling the rate of rotation of the rolls 17 independent of the speed of the wire 7, the difficulties attending the rapidly rotating tube rolls are overcome. In addition, the tube rolls may be rotated as slowly or as rapidly as desired by merely controlling the speed of the chains 9 with respect to the wire 7. The chains may be driven by any suitable variable speed drive (not shown). For example, with a screen speed of 1200 feet per minute, chains 9 may be driven at a speed of 1150 or 1250 feet per minute. In the former case the rolls 17 will be so rotated as to have a peripheral speed of 50 feet per minute in a clockwise or positive direction and in the latter case the rolls will have a peripheral speed of 50 feet per minute in a counterclockwise or negative direction. Of course, any desired difference of screen speed or chain speed may be adopted and the above example is not to be construed as a limitation.

In view of the fact that the difficulty hereinbefore described has two factors, namely, roll speed and the presence of liquid carrier on or adjacent the rolls, the disruptive effect of the rapidly rotating rolls will not be as pronounced when the rate of dehydration of the pulp upon the screen decreases below a critical point. Consequently, it may be necessary to mount only that portion of the tube rolls of the machine adjacent the breast roll upon the endless chains. For instance, it may be found sufficient to mount only those tube rolls within 6 or 8 feet upon the breast roll of the moving chain. However, my invention broadly contemplates mounting all, or a number less than all, upon a moving carrier.

As a feature of my present invention, the wire 7 carried by the translated tube rolls is maintained as undisturbed and quiescent as possible. A serious problem is presented in bringing the tube rolls 17 into initial contact with the lower surface of the screen when said rolls are carried by an articulated conveyor such as the chains 9. The links of the chain being straight must of necessity merely approximate the curvature of the sprocket wheel 8. Consequently, I have journaled the roll shafts 18 at axes of articulation of the links. By this arrangement, although the links of the chains will dispose themselves along chordal lines when the chains travel over the sprocket wheels, the pivotal axes of the rolls will describe a true circular path. Hence, rolls 17 will be brought into supporting contact with the screen or wire 7 at the top of sprocket wheels 8 along a line or plane tangent to the arc described by the outermost surfaces of said rolls in passing around sprocket 8. Therefore, the screen carrying the newly laid fibers will not be jarred by the rolls coming into contact with the wire which action, of course, would disturb the fiber formation.

I claim as my invention:

1. In combination, a paper making machine comprising a frame, an endlessly moving paper forming screen carried by said frame, a plurality of rotatable tube rolls over which said screen moves and upon which said screen is supported, a sprocket chain conveyor for moving said tube rolls laterally in a plane parallel to the plane of motion of said screen, said tube rolls being journaled in the links of said chain, the axes of said tube rolls being in a plane substantially coincident with the plane of the axes of the pintle pins of said chains, said frame being provided with a channel opening towards, and on each side of said conveyor, said channels paralleling a portion of the path of travel of said screen, a bearing carried at each end of each of said tube rolls adapted to travel in said channels whereby movement of said tube rolls at right angles to said channels is limited.
- 5 2. In combination, a paper making machine comprising a frame, an endlessly moving paper forming screen carried by said frame, a plurality of rotatable tube rolls over which said screen moves and upon which said screen is supported, a conveyor comprising two oppositely positioned endlessly moving chains, said tube rolls being rotatably carried between said chains, the axes of said tube rolls being positioned in substantially the plane of the longitudinal axes of said chains, said frame being provided with a channel opening towards, and on each side of said conveyor, said channels paralleling a portion of the path of travel of said screen, a bearing carried at each end of each of said tube rolls adapted to travel in said channels whereby movement of said tube rolls at right angles to said channels is limited.
- 10 3. In combination, a paper making machine comprising a frame, an endlessly moving paper forming screen carried by said frame, a plurality of rotatable tube rolls over which said screen moves and upon which said screen is supported, a conveyor comprising two oppositely positioned endlessly moving chains, said tube rolls being rotatably carried between said chains, the axes of said tube rolls being positioned in substantially the plane of the longitudinal axes of said chains, said frame being provided with a channel opening towards, and on each side of said conveyor, said channels paralleling a portion of the path of travel of said screen, a bearing carried at each end of each of said tube rolls adapted to travel in said channels whereby movement of said tube rolls at right angles to said channels is limited.
- 15 4. In combination, a paper making machine comprising a frame, an endlessly moving paper forming screen carried by said frame, a plurality of rotatable tube rolls over which said screen moves and upon which said screen is supported, a conveyor comprising two oppositely positioned endlessly moving chains, said tube rolls being journaled in said oppositely positioned chains and being disposed between said chains, said frame being provided with a channel opening towards, and on each side of said conveyor, said channels paralleling the upper run of said screen, a bearing carried at each end of each of said tube rolls adapted to travel in said channels whereby movement of said tube rolls at right angles to said channel is limited.
